(No Model.)

M. BRETHERTON.

MITER BOX.

No. 359,663.

Patented Mar. 22, 1887.

UNITED STATES PATENT OFFICE.

MARTIN BRETHERTON, OF WASHINGTON, DISTRICT OF COLUMBIA, ASSIGNOR
OF ONE-HALF TO CLEMENT CRESSON, OF PHILADELPHIA, PA.

MITER-BOX.

SPECIFICATION forming part of Letters Patent No. 359,663, dated March 22, 1887.

Application filed May 24, 1886. Serial No. 203 149. (No model.)

To all whom it may concern:

Be it known that I, MARTIN BRETHERTON, a citizen of the United States, residing at Washington, in the District of Columbia, have invented new and useful Improvements in Miter-Boxes, of which the following is a specification.

My invention relates to mitering apparatus, and the purpose thereof is to provide a miter-box in which a common hand-saw or a tenon-saw may either one be used without change in or alteration of the guides.

It is my purpose, also, to provide a miter in which the working-base shall be of wood and shall be so constructed that it may easily and quickly be removed and replaced, whereby the saw cannot, under any circumstances, be injured by coming into contact with metal.

It is a further purpose of my invention to so construct and combine the parts composing the miter-box that one part may be permanently attached to a suitable base or support, while the other may be shifted thereupon to give the required angle to the saw, either by swinging the latter or by the application of slight force to the movable part, the exact angle of the cut being indicated to the operator by a gage upon one of the adjacent sliding parts.

My invention, finally, contemplates an improved construction and arrangement of the saw-guides, whereby the apparatus is simplified in operation and materially cheapened in cost, a simple attachment whereby the ordinary tenon-saw may be used for kerfing, and novel means for connecting the saw-guides and fastening the parts of the box, by which I obtain great strength and perfect accuracy and promote the simplicity and ease of operation of the entire mechanism.

The invention consists in the several novel features of construction and combinations of parts hereinafter fully set forth, and definitely pointed out in the claims annexed to this specification.

Referring to the drawings forming part of this specification, Figure 1 is a perspective view of the entire machine. Fig. 2 is a plan view of the same. Fig. 3 is a transverse vertical section. Fig. 4 is a detail view of one of the parts detached.

In the said drawings, the reference-numeral 1 designates one longitudinal half part of the box, which is preferably constructed as to its body portion of a single casting having a horizontal flooring-piece, 2, and a parallel flange, 3, both the parts last named having straight edges. Legs 4, or other similar supports, may be formed on or attached to the box-section, and upon the portion indicated above I propose to provide the legs or other supports with eyes 5 to receive screws or other devices whereby the rear sections of the box may be permanently attached to the bench 6 or other support. If desired, the flange 3 may be provided with a shallow groove, 7, in its vertical edge, for a purpose presently to be shown.

The front box-section, 1^a, is the counterpart in all essential respects of the section above described, differing only in the lower or foot flange, 3, being provided with a spline, 7^a, which seats in the channel 7 in the flange of the opposite section. This feature is not absolutely essential, however, since the meeting edges of these flanges may be left perfectly flat; but the groove and spline prevent the one section of the box from riding up or departing from a true relation to the other or opposite section.

The entire miter-box is composed of four of these sections—two in front and two in rear—a central space, 8, being left, within which the saw may work. Upon the two front sections, 1^a, are formed or attached legs or other supports, in which are journaled rolls 9, by which the front sections may easily be shifted upon the rear sections. These parts are connected together by tie-bolts 30, having nuts 31 upon their outer ends, and which pass through slots 10, formed horizontally between the floor-pieces and the foot-flanges. These slots may be formed in both rear and front sections; but by extending them somewhat in length it will be sufficient if they are formed in the front half-boxes only.

Upon inwardly-projecting ledges or shelves 2^a, arranged above the floor-pieces 2, are laid the working-bases 11, each of which is of equal width with the ledge, to which it is bolted or otherwise secured, and extends from the outer end of one box-section 1^a to the other end of the other front box-section. The meeting

edges of these working-bases 11 are flush, and so constructed as to move easily upon each other as the box is adjusted for the cut.

Upon one of the front sections 1^a adjacent to the central opening for the saw, is cast or mounted a square boss, 12, having a central vertical cylindrical opening, which receives the rounded end of an upright, 13. Near its lower end a horizontal slot, 14, is cut nearly through the boss 12, and the foot of the upright, which extends below the slot, is also rounded and enters an opening in the base of the part 12, as shown at 15, Fig. 3. That portion of the upright which lies in the slot 14 is squared and receives the eye 16 upon one end of a tie-bolt, 17. (Shown in detail in Fig. 4.) This tie-bolt is formed in two parts, 17 and 17^a, the former sliding within the latter, for a purpose presently to be shown.

Upon the upright 13 is mounted the saw-guide 18, consisting of an L-shaped block having a rectangular opening in the shorter limb to receive the upright which fits within said opening. In the other limb of the block is cut a guide-slot, 19, extending about three-fourths of the width of the block, and of such dimensions that it will admit the back of the common hand-saw. The block-guide 18 is adjustable upon the upright 13.

About midway of the slot 19 is cut an enlargement, 20, of such size as to permit the insertion of a common tenon-saw. The position of this enlargement relatively to the guide-slot 19 is not specially important, as it might 35 be formed at the extreme upper end of the latter; but by giving the back of the common saw a positive support above the said enlargement more accurate work may be done with less pains.

Upon the corresponding end of the rear box section is formed or mounted a similar boss, having a construction and function which are in all respects similar to those already described. The two uprights are connected just

above the foot-flanges of the box by means of the tie-bolt 17 17^a, the square eyes thereof fitting upon the squared portions of the uprights lying in the slots 14. As the box-sections 1^a are moved or caused to slide upon the stationary sections, the two uprights will be compelled to turn through an equal arc of revolution and bring the guide-slots 18 into the same straight line, which will cross the box at an angle exactly proportioned to the longitudinal adjustment of the movable box-section upon the stationary section. In fact, the tie-bolt 17 will constantly preserve the guide-slots 19 in exact alignment during all possible adjustments of the box-sections.

Upon the guide-blocks 18 are mounted gage-bars 21, having longitudinal slots 22, which receive set-screws 23, tapped into the guide-blocks, whereby the gage-bar may be adjusted vertically and then clamped securely in position. These bars extend parallel with and adjacent to each of the uprights, the arrangement being such that the lower end of each

will strike upon the top of the boss 13 when the block 18 has descended far enough. These gage-bars are to be used in kerfing, and by adjusting them to the depth of the cut to be made a series of kerfs of exactly the same depth may be made with great rapidity and accuracy.

In order to provide for the speedy and easy adjustment of the guides to any desired angle, I mark upon the edge of the shelf 2^a of one of the sections a gage-scale, 24, Fig. 1, calculated to the various angles to which the miter-box may be adjusted. This construction enables me to give an instantaneous and exact adjustment of the box-sections to any angle.

By my invention I provide a simple, strong, durable, and extremely accurate mechanism for mitering or kerfing, in which the common hand-saw or the tenon saw may be used indifferently, and having all the advantages hereinbefore set forth.

By placing the saw-guide outside of or upon one side of the upright, and thus bringing all the working mechanism from under the saw, I make it possible to use a common saw without injury to the teeth either by cutting down upon metal or by wear upon one side or set of the teeth, the block-guide being only deep enough to make a perfect support and accurate guide for the saw, but leaving its teeth perfectly clear. Also, by dividing the box into four sections and connecting each pair by the wooden working-base only all possibility of injury to the tool is avoided, even should the working-base be wholly cut through by accident or carelessness.

I obtain the adjustment by a rectilinear sliding movement of one-half the box, instead of by a circular motion, by which it has been customary to set the miter, and this construction is rendered possible by the extensible link connecting the uprights, by which, also, the saw-guides are always adjusted into alignment upon all possible angles.

What I claim is—

1. In a miter-box, four separate box-sections arranged in pairs with a space between said pairs, two similar wooden working-bases connecting the front and rear sections, respectively, with each other, and an extensible link extended transversely beneath the box and connecting the front and rear sections, substantially as described.

2. In a miter-box, the combination, with a front and rear section sliding one upon the other, of bosses rigidly mounted on each section, uprights seated in said bosses and carrying the saw-guides, and an extensible link having an eye at each end, which embraces the lower end of each upright and adjusts the angle and preserves the alignment of the saw-guides, substantially as described.

3. In a miter-box, the combination, with a front and rear section sliding one upon the other, of bosses rigidly mounted on the outside of each section, uprights seated in said bosses, guide-blocks having vertical adjustment upon

the angular portion of said guides, and an extensible link having its ends rigidly connected with the ends of said uprights, the guide-blocks being arranged outside of or on one side of the 5 uprights, substantially as described.

4. In a miter-box, the combination, with four box-sections connected longitudinally in pairs, of similar working-bases formed of wood, and adjustable supports for the saw arranged 10 near the middle of the box, a working-space being left between the two front and two rear sections, which space is bridged by the wooden bases only, substantially as described.

5. In a miter-box, the combination, with a 15 two-part rear section, the parts being connected by a wooden working-base and separated by a working-space, of a similar two-part front section, a rigid boss mounted on each adjacent to the working-space, rectangular uprights having cylindrical portions which turn in said bosses, an extensible link rigidly connected with the foot of each upright, guide-blocks adjustable upon the rectangular parts of the uprights, and tie-bolts which pass

through slots in the parts of the front section 25 and have set-nuts turning up against the same, substantially as described.

6. A miter-box having a two-part front section, the parts being separated and connected by a wooden working-base, a rear section of 30 similar construction, uprights journaled in supports on said sections, an extensible link having its ends rigidly connected to said uprights beneath the box, guide-blocks having vertical adjustment on said guides and turning with them, and tie-bolts connecting the front and rear sections, the guide-blocks being each provided with a compound groove or slot 35 to receive either a hand or a tenon saw, and the meeting edges of the sections having a gage 40 marked thereon by which the miter may be set, substantially as described.

In testimony whereof I affix my signature in presence of two witnesses.

MARTIN BRETHERTON.
